UNITED STATES PATENT OFFICE

LEWIS EDMOND WEBSTER, OF WILKES-BARRE, PENNSYLVANIA

SHOVEL HANDLE

Application filed February 15, 1927. Serial No. 168,277.

This invention relates to handles for shovels and other implements and more particularly to handles commonly known as split-D handles wherein the upper end portion of the shaft or stem is bifurcated to form two diverging arms between which, at the upper ends thereof, is inserted the grip bar for the hand of the user.

An object of this invention is to provide a handle of this type which will be strong, durable and will afford the greatest possible protection against injury to the handle and also to the hands of the user.

A further object of the invention is to improve the method of manufacture of this type of handle so that handles may be manufactured cheaply in large quantities and with very little loss from splitting or cracking while forming.

Handles of the split-D type have long been known, having been originally designed for the purpose of economizing in the use of material. The usual split-D handle, it will be remembered, was formed integral with the shaft, the result being a considerable waste of material.

In constructing a handle of the split-D type it has heretofore been the practice to split the main shank centrally for a sufficient distance, steaming the wood and then shaping the handle in clamps.

The grips for these handles are all held in some way with special ferrules fitted on top of the arms or upright portions of the wood, the wooden grips being fastened into the ferrules and riveted together. During the forming operation the wood very often splits and cracks rendering the handle worthless. Furthermore, the handle, being only half the thickness of the shank and weakened from bending, is very frail and delicate and may be fractured by a slight fall.

In constructing a split-D handle in accordance with this invention the above disadvantages have been practically all eliminated, a comfortable, strong handle resulting.

With these objects in view, the invention consists in the method, combinations, details of construction, and arrangements of

parts which will first be described and then more particularly pointed out.

In the drawings—

Figure 1 shows the handle split before forming;

Figure 2 is a front view of the complete handle with parts broken away to show its construction;

Figure 3 is a section on the line 3—3 of Fig. 2;

Figure 4 is a section on the line 4—4 of Fig. 2;

Figure 5 is a section on the line 5—5 of Fig. 2; and,

Figure 6 is a perspective view of the grip.

Briefly, two pressed steel casings 1 and 2 are accurately formed to the desired shape in dies, double seamed as at 3 and assembled into one unit with an opening through which a wood stem 4 may be inserted. Each of the arms 1 and 2 are provided with inturned flanges 1^a and 2^a so arranged that they will embrace the edges of the wood as will presently appear. The wood stem 4, is first turned perfectly and rounded on its end 5 to a uniform radius. The stem is then split, as by sawing through its center, to form two arms 6 and 7, to a length sufficient for forming a handle of suitable size. The edges of the arms may then be accurately rounded to size 70 by passing the stem through a suitable guide.

In order to permit the insertion of the hand grip 8 the ends of the arms are milled off as at 9 in such manner that they may receive the grip and hold it from turning, the grip 8 being also milled out as at 10 (Fig. 6) to provide an accurate fit.

After the wooden handle so formed has been steamed for a sufficient length of time to render it soft for bending, it is inserted with its rounded end foremost into the opening formed by the two parts of the metal casing. In practice this metal casing is held in a jig on a forming machine having a clamp which accurately fits the inside and outside of the casing. The two arms 6 and 7 of the shaft fill the casings 1 and 2 respectively and are given a permanent set in the usual hot room provided for such purposes. The grip 8 previously formed and milled is snapped between 95 100

the metal-encased ends 5 of the handles to fit snugly in the milled portions 9. The upper ends of the casings 1 and 2 are so formed that they extend slightly over the ends of the grip 8, as shown at 11, thus making a smooth finish and taking the place of a ferrule. The grip handle and casing are all secured together by means of a rivet 12 extending longitudinally of the grip, being countersunk at 13, as by punching, to avoid presenting sharp edges to the hand. As a further means of securing the parts and preventing the handle from cracking or splitting another rivet 14 is provided at the lower part of the fork or split.

With this construction there is provided a handle of the split D type having all the strength of the usual wood handle plus the strength of the metal casing. Furthermore, the hands of the user are fully protected from slivering and splintering of the wood.

This construction not only protects the handles from splitting or cracking while in use but also greatly reduces the loss of stems in the process of forming.

From a manufacturing standpoint, the saving of perfectly good stems, avoiding hand operations of fitting ferrules and grips and whittling the corners off with draw knives, makes this handle easily the cheapest handle on the market besides giving the trade a decidedly better handle than is now in use.

What is claimed is:

1. In a split-D handle construction, a main stem having side arms, a pressed metal casing embracing the body of the stem and said arms, a grip between the ends of the arms, said casing forming a ferrule for the ends of the arms and the grip.

2. In a split-D handle construction, a main stem having side arms, a pressed metal casing embracing the body of the stem and said arms comprising two symmetrically formed portions secured together at one end, the opposite ends of said portions being rounded to form ferrules, and a grip fixed between the ends of the arms of the casing.

3. A split-D handle comprising a main bifurcated stem providing arms, a handle grip between the arms, a preformed pressed metal casing embracing the body of the stem and having side arms embracing the arms of the stem, and ferrule-like ends for protecting the joint between the arms and the grip.

4. A split-D shovel handle comprising a main bifurcated stem providing side arms, a grip between said arms, a bifurcated pressed metal casing embracing the body of the stem and also the arms to protect said arms from splintering, means for securing said grip, arms and casing together, and means for securing said casing to the stem.

5. A D-handle comprising a preformed die-shaped metal casing having a tubular hub portion and arms with inturned flanges, a

wood stem embraced by and in close contact with said hub portion and having side arms above said hub portion embraced by and in close contact with the arms and flanges of the casing, and a grip fixed between the ends of the arms of the casing.

6. A shovel handle comprising a main bifurcated stem providing side arms, a grip between said arms, means for securing said grip to said arms, a bifurcated metal casing embracing the body of the stem and also the arms to protect said arms from splintering.

7. A split-D handle comprising a main bifurcated stem providing side arms, a bifurcated pressed metal casing embracing the body of the stem and also the arms to protect said arms from splintering, and a grip fixed between the ends of the arms of the casing.

In testimony whereof, I have hereunto set my hand.

LEWIS EDMOND WEBSTER.
